INKING MECHANISMS FOR ROTARY PRINTING PRESSES

Hans J. Luehrs, Westerly, R.I., assignor, by mesne assignments, to The Cottrell Company, Westerly, R.I., a corporation of Delaware

Application June 12, 1952, Serial No. 293,045

6 Claims. (Cl. 101—365)

My invention is directed to improvements in inking mechanisms for rotary printing presses, in which novel means are employed for pumping the ink in regulable quantities from an ink pressure supply chamber or chambers to the ink distribution to be fed thereby to its co-acting plate cylinder.

My invention is directed more particularly to improvements in the drives for the ink distribution and the ink pumping mechanism.

My invention includes an ink distribution in which the distribution cylinder, which receives the ink from its ink pumping mechanism, will be rotated in a direction to cause its side toward the pumping mechanism to travel upwards irrespective of the direction of rotation of the plate cylinder.

My invention also includes an ink pumping mechanism in which the ink is supplied under pressure from a suitable source or sources to the one or more ink pressure supply chambers, in which chambers the ink will be maintained at a constant and uniform pressure.

My invention also includes various improvements in ink pumping mechanism shown, described and claimed in my copending application filed November 24, 1951, its Serial No. being 258,053 now Patent No. 2,672,812, March 23, 1954.

My invention also includes novel operative connections between the main drive and the ink distribution and between the ink distribution and the ink pumping mechanism.

My invention includes more particularly a variable speed connection between the main drive shaft and the ink distribution cylinder shaft and a free-wheeling overrunning clutch between the distribution cylinder shaft and the drive for the ink pumping units; thus providing for the proper range of relative speeds between the ink distribution and the ink pumping mechanism.

My invention also includes means whereby each of the groups of ink pumping units may be removed independently of the other groups for facilitating the cleaning of the several elements of the ink pumping mechanism.

My invention also includes provision for oscillating the two ductor rollers either directly or indirectly between the distribution cylinder and the ink drum of the ink distribution, to permit the rotation of the plate cylinder in either direction, as required, without affecting the direction of rotation of the distribution cylinder.

A practical embodiment of my invention is represented in the accompanying drawings, in which:

Fig. 1 represents a detail front view, partly in section, of the work side of the inking mechanism;

Fig. 2 represents a detail front view, partly in section, of the gear side of the inking mechanism;

Fig. 3 represents a detail plan view showing the variable speed drive between the main drive and the ink distribution cylinder shaft.

Fig. 4 represents a detail plan view showing the free-wheeling overrunning clutch between the distribution

2

cylinder and the drive shafts for the ink pumping mechanism;

Fig. 5 represents a detail vertical cross-section taken in the plane of the line V—V of Fig. 1, looking in the direction of the arrows, the ink pump valve being shown at the middle of its stroke with the valve plunger port located between, and shut off from, the ink pressure supply passage and the ink discharge passage;

Fig. 6 represents a similar view with the valve plunger port open to the ink pressure supply passage, and shut off from the ink discharge passage;

Fig. 7 represents a similar view with the valve plunger port open to the ink discharge passage, and shut off from the ink pressure supply passage;

Fig. 8 represents, diagrammatically, one form of ink distribution, and

Fig. 9 represents, diagrammatically, another form of ink distribution.

The ink distribution shown herein includes, an ink distribution cylinder for receiving the ink from the ink pumping mechanism. The ink roller for the distribution cylinder is denoted by 1. The upper and lower oscillating ductor rollers are denoted by 3 and 4. The ink drum is denoted by 5. The upper ink rollers 6 and 7 lead from the ink drum 5 to the upper plate cylinder inking rollers 8 and 9. The lower ink rollers 10 and 11 lead from the ink drum 5 to the lower plate cylinder inking rollers 12 and 13. The upper and lower inking rollers 14 and 15 contact the ink drum 5.

The plate cylinder 16 may be driven either clockwise or anti-clockwise from any suitable source of power.

When the plate cylinder 16 is driven anticlockwise, as shown in Fig. 8, the ductor rollers 3 and 4 are oscillated to alternately contact the distribution cylinder 1 and their respective ink rollers 14 and 15, which ink rollers in turn contact the ink drum 5. In this form, the ink drum 5 is also driven anti-clockwise.

When the plate cylinder 16 is driven clockwise, as shown in Fig. 9, the ductor rollers 3 and 4 are oscillated to alternately contact the distribution cylinder 1 and the ink drum 5 which, in this form, is also driven clockwise. In both of the forms shown in Figs. 8 and 9, the ink distribution cylinder 1 is driven clockwise, so that its side toward the ink pumping mechanism travels upward, thereby preventing excessive ink leakage downwardly between the distribution cylinder 1 and the ink rail 20.

The shaft A of the main drive for the inking mechanism is shown as connected through a variable speed drive B (as a P.I.V. drive) to the shaft 19 of the distribution cylinder 1. This drive may provide, for instance, a range of from 378.2 to 756.4 r.p.m.

In coaction with the variable speed drive B and varying at the same rate, the cross drive shaft C drives the interconnected drive shafts 25 (to be hereinafter described) of the ink pumping mechanism through a free-wheeling overrunning clutch D which cross shaft C is shown as geared at one end, as shown at 17, to the distribution cylinder shaft 19 and at its other end, as shown at 18, to the said clutch D. The speed reduction through this drive provides a range of from 75 to 150 r.p.m. which is equal to the same number of strokes per minute of the pumps of the ink pumping mechanism, to be immediately described.

This ink pumping mechanism is shown as including the following elements:

The ink rail 20 extends along the upwardly traveling side of the ink distribution cylinder 1. This ink rail 20 is shown as having a trough in its top surface, which trough is divided by separately removable partitions 21 into a plurality of ink pressure supply chambers 22 having individual inlets 23, through which the ink is supplied under

pressure to the chambers 22 from a suitable source or sources of ink pressure supplies.

A plurality of oil tanks 24 for lubricating the groups of pumping units are individually removable, which tanks are preferably of one page width. These oil tanks 24 are shown as mounted along the top of the ink rail 20 in position to close the open tops of the ink pressure supply chambers 22. The inner walls of these oil tanks are shown as concave to conform to the adjacent side of the ink distribution cylinder 1.

The ink pumping units are located within the oil tanks 24 over their ink pressure supply chambers 22. These ink pumping units are shown as arranged in groups which are removable with their said oil tanks 24.

The alined short shafts 25 for driving the group of ink pumping units are mounted in the end walls of the oil tanks 24. These drive shafts 25 are arranged one for each group of ink pumping units. These shafts 25 are also removably connected at their adjacent ends so as to permit the shafts to be individually removed with their respective oil tanks 24 and their respective groups of printing units, for facilitating the cleaning of the ink pumping mechanism.

These interconnected alined drive shafts 25 are shown as being driven at the required speed from the ink distribution cylinder shaft 19 through the before-mentioned free-wheeling overrunning clutch D of any well known or approved construction.

As all the ink pumping units of the several groups are similar in construction, arrangement and operation, one only of these ink pumping units will be specifically described herein.

Each ink pumping unit includes an eccentric 27 which is secured on its short drive shaft 25 in the desired rotative position with respect to the eccentrics of the other pumping units of the group within the tank 24, to avoid torque complications.

A strap 28 surrounds the eccentric 27, and the arm 29 of the strap is pivoted to the adjacent end of a horizontally disposed valve 30 slidable in its casing 31 fixed on the bottom of the oil tank 24. This slide valve 30 has a vertical cross port 32 therethrough for the reception of a sliding plunger 33, which is pivoted to the lower end of a swinging link 34. The upper end of this swinging link is pivoted to the short arm 35 of a rock lever pivoted at 36 within the oil tank 24. The long arm 37 of this rock lever is normally held by a spring 38 against the upper end of a thumb screw 39 threaded through the bottom of the oil tank 24. This thumb screw 39 may be turned to adjust the position of the long arm 37 of the rock lever with respect to the path of the eccentric strap 28, for varying the stroke of the plunger 33.

A short ink pressure supplied passage 40 leads upwards through the bottom of the oil tank 24 and the valve casing 31 to the lower side of the valve 30 in position to coincide with the plunger port 32 when the slide valve 30 is moved to the limit of its inward movement.

An ink pressure discharge passage 41 leads downwardly from the lower side of the valve 30 and thence laterally along the bottom of the oil tank 24 to the upwardly traveling side of the ink distribution cylinder 1. The lower end of this plunger port 32 coincides with the upper end of the discharge passage 41 when the slide valve 30 is moved to the limit of its outward movement.

The manually operated means for simultaneously silencing a selected group of ink pumping units comprises the following elements: A rock shaft 42 is mounted in the ends of its oil tank 24. A plurality of arms 43 (two for each tank) are fixed on the rock shaft 42 in position to be swung by a hand lever 44 fixed on the rock shaft 42 outside the oil tank 24, to cause the pins 45 on the arms 43 to engage and lift the long lever arms 37 out of the path of the eccentrics and to releasably hold these arms in such position. This upward movement of the

long lever arms 37 will cause the short lever arms 35 to depress the valve plungers 33 to a position which will substantially close the vertical plunger port 32. The hand lever 44 may be provided with a sliding latch 46 for engaging either of the recesses 47 in a quadrant 48 carried on the oil tank 24 to hold the hand lever in both of its positions.

In operation, the eccentrics 27 are rotatably adjusted around their shafts 25 so that a substantially continuous flow of ink will be pumped to the distribution cylinder 1. The throw of the valve plungers 33 may also be separately adjusted by the thumb screws 39 which engage the long arms 37 of the rock levers which reciprocate the plungers 33. This permits the ink to be supplied in regulable quantities to the distribution cylinder 1.

The rotation of the shafts 25 will cause the pump valves 30 to reciprocate to bring their plunger ports 32 into alternate communication with the ink pressure supply passages 40 and the ink pressure discharge passages 41. As the plunger ports 32 open communication to the ink pressure supply passages 40, the valve plungers 33 will be withdrawn to permit the plunger ports 32 to be filled with the ink under pressure from the ink pressure supply chambers 22. As the pump valves 30 slide into position to bring the plunger ports 32 into communication with the ink pressure discharge passages 41, the downward movement of the plungers 33 will force the ink through the said discharge passages 41 to the adjacent side of the ink distribution cylinder 1.

It will be noted that the eccentric straps 28 not only reciprocate the pump slide valves 30, but also rock the lever arms 35 and 37 to reciprocate the plungers 33.

When it is desired to silence a group of the pumping units within their oil tank 24, the hand lever 44 is swung to the position shown in dash-dot lines in Fig. 5; thereby causing the pins 45 mounted on the arms 43 of the rock shaft 42 to raise the long lever arms 37 out of the path of the eccentric straps 28.

It will be noted that when the supply of ink is cut off, the continued reciprocation of the valves 30 by the rotation of the eccentrics 27 will be sufficient to cause the links 34 to slightly reciprocate the plungers 33 and thereby prevent the sticking of the parts due to the hardening of the ink.

The subject matter shown and described but not claimed herein, covering the plate cylinder operable to rotate in either direction in combination with the ink distribution cylinder, operable to rotate in one direction only, irrespective of the direction of rotation of the plate cylinder, forms the subject matter of my co-pending divisional application filed July 13, 1954, its Serial No. 442,960, now U.S. Patent No. 2,811,105.

It will be understood that various changes may be resorted to in the form, construction and arrangement of the several parts without departing from the spirit and scope of this invention, and hence it is not intended to be limited to the particular embodiments shown and described herein.

What I claim is:

1. An inking mechanism for rotary printing presses comprising, an ink distribution cylinder, an ink rail located along the upwardly travelling side of the said cylinder, a trough located along the top surface of the said ink rail, which trough is divided by partitions into a plurality of alined ink pressure chambers having individual ink pressure supply inlets, a plurality of alined oil tanks mounted on the top of the ink rail in position to close the open tops of said chambers, a plurality of alined separate groups of ink pumping units located within their respective oil tanks, passages leading from the ink pressure supply chambers to their respective ink pumping units and ink discharge passages leading from the ink pumping units to the upwardly travelling side of the said ink distribution cylinder.

2. An inking mechanism according to claim 1 in which the trough dividing partitions are separately removable.

3. An inking mechanism according to claim 1, in which the groups of ink pumping units include interconnected alined short drive shafts.

4. An inking mechanism according to claim 1, in which the oil tanks are separately removable.

5. An inking mechanism according to claim 1, in which the groups of ink pumping units include interconnected alined short drive shafts which are removable with their respective oil tanks.

6. An inking mechanism according to claim 1, in which the groups of ink pumping units include interconnected alined short drive shafts, and in which the oil tanks are separately removable with their ink pumping units and interconnected alined short drive shafts.
